FACING MACHINE

James M. Kirchberg, New Orleans, La.

Application August 13, 1938, Serial No. 224,801

9 Claims. (Cl. 51—100)

This invention relates to improvements in facing machines, especially of the type used in conjunction with shaping the lay of the mouth-piece for a musical wind instrument. Mouth-pieces, such as are herein contemplated, are currently used on saxophones, clarinets and similar musical wind instruments. The so-called lay comprises the seat portion of the mouth-piece over which the reed is clamped. It is common practice in modern orchestras to have an artist play a number of wind instruments in succession, and for a purpose such as this it is highly desirable, if not essential, to have each mouth-piece in perfect accord. That is to say, to have the lays 10 of the mouth-pieces identically shaped so that each reed will be in the precise relationship to the lay as is every other reed, thus enabling the player to blow into the instrument without having to adapt himself to changed reed conditions 15 which would otherwise be present.

Another requirement which is currently made by the players of musical wind instruments is that of several mouth-pieces for a single instrument, each with slightly different curve characteristics of the respective lays, so that different musical effects can be gotten because of the variations that will be had in the relative positions of the reeds.

A further requirement which is to be met is the 30 working-in of minute variations of measurements in the lay of a mouth-piece so as to suit the requirements of any particular artist. With these statements in mind the objects of the invention are as follow:

35 First, to provide a machine for facing mouth-pieces for clarinets and saxophones with speed and accuracy.

Second, to provide for the adjustment of the 40 template relative to the mouth-piece position so that the length of the curvature of the so-called lay can be varied, thus enabling making several mouth-pieces for one instrument, each with slightly different characteristics for the reed.

45 Third, to provide for the making of perfectly matched mouth-pieces for several wind instruments, so that the player can blow each one in turn and have each mouth-piece in perfect accord.

50 Other objects and advantages will appear in the following specification, reference being had to the accompanying drawings, in which:

Figure 1 is a side elevation of the improved facing machine.

55 Figure 2 is a perspective view of a mouth-piece

illustrating the lay which the machine is adapted to face.

Figure 3 is a sectional view of the mouth-piece holder, parts being shown in elevation.

Figure 4 is a cross section taken on the line 4—4 of Fig. 3.

Figure 5 is a cross section taken on the line 5—5 of Fig. 1.

Figure 6 is a plan view of the machine.

Figure 7 is a cross section taken on the line 7—7 of Fig. 1.

Figure 8 is a cross section taken on the line 8—8 of Fig. 6.

Figures 9 and 10 are detailed views of the two screw shafts.

Reference is first made to Fig. 2 which illustrates a well known type of mouth-piece 1. This mouth-piece is customarily made of Bakelite, although not necessarily so. The mouth-piece is, obviously, hollow, as indicated at 2, the location of the lay 3 in reference to the hollow interior being such as to produce a wind opening 4. The lay 3 extends from the base 5 of the mouth-piece to the tip 6. Its purpose is to provide a seat for a reed (not shown), the latter usually being clamped to the heavy part of the mouth-piece so that the reed is left free to vibrate in reference to the tip 6.

The foregoing lay 3 is struck on a curve mainly at 7 in the region of the tip 6. This curve, although slight, is the involute of a circle, that is to say, it is on a spiral order rather than any part of a true circle. It is the purpose of this machine to grind the lay 3 from base to tip and in order that any number of mouth-pieces 1 may be identically shaped, use is made of a template 8, (Fig. 1).

This template may comprise a strip of material of any suitable kind, for example, hard wood, fiber, metal, etc. The template is fairly thick 40 (Fig. 7). Its top side 9 is usually straight but the bottom side 10 has a contour of the identical shape which it is desired to reproduce in the lay 3, the only difference being that the contour 10 is greatly magnified. The magnification herein adopted is 8 to 1. This enables the template 8 to be shaped exactly as required, minute variations being readily worked into the contour side 10 because the latter is sufficiently large to be readily seen by the workman.

With the mouth-piece 1 and the template 8 in mind, the latter controlling the shaping of the lay 3, reference is made to Fig. 1 for the details of the machine employing these members. The machine is generally designated 11. It comprises 55

a bed 12 which has legs 13. A pair of bearings 14 on one side of the machine (Fig. 6) support a screw shaft 15 which has threads 16. Similarly a pair of bearings 17 on the other side of the machine support a screw shaft 18 which has threads 19. The character of the foregoing threads is illustrated in Figs. 9 and 10. Square threads are preferred, as shown.

A standard 20 (Fig. 1) made integral with the bed 12, supports a hinge pin 21 on which a frame 22 is rockably mounted (Fig. 5). This frame is the common carrier of the mouth-piece 1 and template 8. The manner in which the mouth-piece 1 is carried is as follows: A holder generally designated 23 (Figs. 1 and 3) comprises a rod 24 designated 23 (Figs. 1 and 3) comprises a rod 24 which terminates in a down-turned clamp 25 (Fig. 4). The clamp is actuated by a screw 26. An expansion element 27, having a threaded base 28, nut 29 and stem 30 is held by the clamp 25. The stem 30 is inserted in the clamp whereupon the screw 26 is tightened. After inserting the split element 27 into the mouth-piece 1, the nut 29 is backed off enabling the expansion of the jaws. It is thus that the mouth-piece is rigidly held in position.

A compound rest, generally designated 31 (Figs. 1 and 8) provides the mount for the mouth-piece holder 23. Said rest consists of an upright slide 32 (Fig. 8) in one end of which the rod 24 is secured by the clamping device 33. The slide 32 is vertically adjustable by a screw 34 which has bearings at 35 in a horizontal slide 36. This slide is horizontally adjustable by a screw 37 which has bearings at 38 (Figs. 1 and 6) in an upstanding collar 39 (Fig. 6) on the frame 22, of sufficient size to contain all moving parts of the compound rest 31.

The manner in which the template 8 is carried is as follows: The frame 22 which is fairly heavy at its hinge end (Fig. 6) tapers into a bar 43. This bar is enlarged to provide a pair of pendent plates 41 (Fig. 7) which are spaced at 42 and have a series of bolts 43 to compose a clamp. The template 8 is inserted in the space 42, the straight side 9 being up. The bolts 43 are then screwed home to secure the template in place. The latter is adjustable both up and down and endwise prior to tightening the bolts 43, to dispose the contour side 10 in any desired relationship to the ball end 44 of a feeler pin 45.

Mention of the grinding wheel 46 is made at this point in order to show that the top periphery thereof coincides with an axis 47 which passes through the center of the hinge pin 21 and touches the top of the ball 44. The adopted relationship of the contour side 10 to the axis 47, obtained by the adjustment of the template 8, is reproduced on a reduced scale of the mouth-piece 1 whereon the lay 3 will bear the same relationship to the axis. The adjustment of the template 8 is a matter of experiment and will be supplemented by suitable markings both on the template and on the clamp 41, so that a given position of the expansion element 27 of the holder 23 will provide the operator with a reliable index as to the shape and position of the mouth-piece lay.

A pair of carriages 48, 49, is slideable on guide rods 50 (Figs. 7 and 8) of the bed 12. The carriages are held down by plates 51. The carriage 48 has an arm 52 (Fig. 6) which terminates in a head 53 (Fig. 8) in engagement with the threads 16 of the shaft 15. Similarly the carriage 49 has an arm 54 (Fig. 6) terminating in a head 55 (Fig. 7) having engagement with the threads 19 of the shaft 18. The shaft 18 is driven by a pulley and

belt arrangement 56, 57 (Fig. 1) from a reversible type electric motor 58.

The shaft 15 is driven from the shaft 18 by a gear train consisting of a pinion 59 on the shaft 18 with an idler 60 and a large gear 61 on the shaft 15. The ratio of the gears is such that the carriage 49 will be moved along the bed 12 eight times as fast as will the carriage 48, thus agreeing with the scale of magnification of the template 8 over the length of the lay 3.

The previously mentioned grinding wheel 46 is attached to a shaft 62 (Fig. 8) which is journaled in a bearing 63. This bearing has a stem 64 which is adjustable in a socket 65 so as to properly position the grinding wheel 46 in reference to the axis 47. The grinding wheel is driven by a pulley and belt arrangement 66, 67, from a motor 68 affixed to the carriage 48.

The operation is readily understood. The amplitude of motion of the feeler pin 45 is designated 20 by the boundary lines 69, 70 (Fig. 1). The distance between these lines is eight times the length of the lay 3 (Fig. 2) from the base 5 to the tip 6. The feeler pin 45 is to be regarded as traveling in the direction of the arrow a, having started at 25 the boundary line 69. Both carriages 49, 48, are traveling in the same direction. The carriage 49, however, travels eight times faster than the carriage 48.

Thus the zenith of the grinding wheel 46 will 30 traverse the mouth-piece 1 from tip to base while the feeler pin 45 traverses the contour side 10 from line 69 to line 70. The grinding wheel 46 is in operation, the result being a grinding of the mouth-piece to form the lay 3.

The latter is given a shape identical with the contour side 10 only on a reduced scale because of the fact that as the ball end 44 slides along the contour side 10, the entire frame 22 will be rocked on its hinge pin 21, the mouth-piece 1 40 being raised accordingly so that just enough material is ground off.

The forward motion (arrow a, Fig. 1) of the carriages 49, 48 is produced by one direction of rotation of the motor 58. When the feeler pin 45 reaches the line 70 the motor 58 will be reversed by any known type of reversing switch (not shown) so that the parts are transported to their starting positions. In conclusion it is desired to state that the designation of the wheel 46 as a grinding wheel is not to be regarded as a limitation. This term is uniformly used in this disclosure and in many instances will comprise an actual grinding wheel. But there are also instances in which the element 46 may and will 55 consist of a milling cutter or any known cutting device which will perform the work satisfactorily.

I claim:

1. A facing machine comprising a mouth-piece holder, a grinding wheel to cut a lay upon a mouth-piece secured on the holder, a carriage for the grinding wheel, a template having a side contoured according to the shape to be given to the lay, a frame carrying the mouth-piece holder and template, means to move the carriage to advance the grinding wheel along the mouth-piece, and means traversing the contoured side of the template to simultaneously rock the frame.

2. A facing machine comprising a mouth-piece holder, a grinding wheel to cut a lay upon a mouth-piece secured on the holder, a carriage for the grinding wheel, a template having a side contoured on a magnified scale, with a shape to be given to the lay on a small scale, a frame carrying the mouth-piece holder and template, 75

means to move the carriage to advance the grinding wheel from tip to base of the mouth-piece, and means traversing the magnified contour of the template to rock the frame during the same time period taken by the grinding wheel to traverse the mouth-piece.

3. A facing machine comprising a mouth-piece holder, a grinding wheel to cut a lay upon a mouth-piece secured on the holder, a pair of carriages, one of them having the grinding wheel mounted thereon, a template having a side contoured on a magnified scale with a shape to be given to the lay on a small scale, a frame carrying the mouth-piece holder and template, means on the other carriage to feel the template contour, and separate means to move the carriages at different speeds so that the grinding wheel and feeler means traverse the respective small-scale mouth-piece and magnified contour in the same time period, the action of the feeler means rocking the frame.

4. A facing machine comprising a mouth-piece holder, a grinding wheel to cut a lay upon a mouth-piece secured on the holder, a carriage for the grinding wheel, means to move the carriage to advance the grinding wheel from tip to base of the mouth-piece, a template having a side contoured according to the wanted profile of the lay but on an enlarged scale, a frame carrying the mouth-piece holder and the template, and means to traverse the template contour to rock the frame in the same time period as required for the grinding wheel to traverse the lay.

5. A facing machine comprising a mouth-piece holder, grinding means to cut a lay upon a mouth-piece securely carried by the holder, a movable carriage for the grinding wheel, a template of large proportions relative to the size of the mouth-piece, connected to a holder and having a side contoured to form a magnified pattern for the lay, feeler means to traverse the template to shift the holder in respect to the grinding means, and means to simultaneously move the carriage and the feeler means at different rates respectively to the extent of the lay and to the extent of the magnified contour of the template.

6. A facing machine comprising a bed, a pair of carriages movably guided upon the bed, a feeler pin on one of the carriages, a revoluble grinding wheel on the other carriage, a frame

hinged at one end upon the bed, a template attached to the other end of the frame, said template having a side bearing upon the feeler pin, and said side having a lay contour of magnified proportions, a holder carried by the frame having means to hold a mouth-piece in contact with the grinding wheel, a pair of screw shafts journaled on the bed, means connecting the respective carriages to the screw shafts, and means to turn the screw shafts at different speeds so as to advance the feeler pin along the template in the same time period that the grinding wheel is advanced along the mouth-piece.

7. A facing machine comprising a frame, a hinge pin on which the frame is rockable, a holder securing a mouth-piece on the frame, a feeler pin, a revoluble grinding wheel, the zenith of which coincides with an axis common to the hinge pin center and tip of the feeler pin, a template attached to the frame having a side shaped on a large scale to the desired contour of the mouth-piece lay, the plane of the shaped side crossing said axis, and separate means advancing the feeler pin and grinding wheel in respect to the template and mouthpiece at speeds matching the disparity in size of the mouth-piece to the shaped template side.

8. A facing machine comprising a frame, a hinge pin on which the frame is rockable, a holder securing a mouth-piece on the frame, a feeler pin, a revoluble grinding wheel, means to adjust the grinding wheel so that its zenith coincides with an axis common to the tip of the feeler pin and center of the hinge pin, means to adjust the holder until the mouth-piece touches the grinding wheel, a template attached to the frame, the plane of one side crossing the axis, touching the feeler pin and being contoured on a large scale to accord with the shape of the lay to be ground on the mouth-piece, means to advance the grinding wheel along the mouth-piece, and means to advance the feeler pin along the template at a relatively high speed.

9. In a facing machine, a frame having an upstanding collar, a compound rest housed in the collar consisting of a slide horizontally movable in the collar, and a second slide vertically movable in the previously mentioned slide, a bar constituting the terminal of the frame, and a clamp structure embodied in the bar along one side.

JAMES M. KIRCHBERG.
